(57) **CLAIM**

The ornamental design for a resistance breathing device, as shown and described.

DESCRIPTION

FIG. 1 is a top perspective view of a resistance breathing device showing my new design;

FIG. 2 is a front elevational view thereof;

FIG. 3 is a rear elevational view thereof;

FIG. 4 is a left side elevational view thereof;

FIG. 5 is right side elevational view thereof;

FIG. 6 is a top plan view thereof; and,

FIG. 7 is a bottom plan view thereof.

The broken lines in the drawings illustrate stitching on the resistance breathing device that forms part of the claimed design. The dotted lines in the drawings depict portions of the resistance breathing device that form no part of the claimed design.
